Primary Examiner — Robin V Webster*Assistant Examiner* — J. Thorn, Sr.(74) *Attorney, Agent, or Firm* — Ferguson Case Orr Paterson(57) **CLAIM**

The ornamental design for a kinematic bra, as shown and described.

DESCRIPTION

FIG. 1 is a front isometric view of a kinematic bra in accordance with the new design;

FIG. 2 is a front view thereof; and,

FIG. 3 is a rear view thereof.

The broken lines shown in the drawings represent stitching in the fabric.
